UNITED STATES PATENT OFFICE.

HOWARD J. POTTS, OF READING, PENNSYLVANIA, ASSIGNOR TO THE GENERAL ADVERTISING CO., OF READING, PENNSYLVANIA, A CORPORATION OF PENNSYLVANIA.

DISPLAY-CARD WITH EASEL ATTACHMENT.

1,117,085.

Specification of Letters Patent.

Patented Nov. 10, 1914.

Application filed June 2, 1914. Serial No. 842,373.

To all whom it may concern:

Be it known that I, HOWARD J. POTTS, a citizen of the United States, residing at Reading, in the county of Berks and State 5 of Pennsylvania, have invented certain new and useful Improvements in Display-Cards with Easel Attachments, of which the following is a specification.

This invention relates particularly to advertising signs, or like display cards, made up of a display facing sheet and a reinforcing backing sheet arranged to give form and rigidity thereto; and it consists in combining with such a device a simple easel-leg 15 attachment involving no projection therefrom normally, though adapted to automatically swing into operative easel position when released for that purpose.

The invention is fully described in connection with the accompanying drawings and the novel features are specifically pointed out in the claims.

Figure 1 is a perspective rear view of an advertising sign or display card embodying 25 my invention. Fig. 2 is an enlarged vertical cross-section of the same, showing the easel leg in operative position as in Fig. 1; the normal closed position thereof being indicated however, in dotted lines, and also 30 an intermediate position indicating the manner of engaging or disengaging the free end thereof.

The drawing shows a display card which is made up of a display facing 5, as of celluloid sheeting, and a contacting backing sheet 6, preferably of sheet metal, the marginal portions 7 of which rectangular sheets are jointly doubled-over rearwardly and clenched against the adjacent border portions 8 of the 40 card, so as to tightly and rigidly unite said sheets. The main construction thus briefly referred to is already well known in the art, and the present invention consists in the hereinafter described improvements.

45 The purpose of my invention is to provide an improved easel leg attachment to such a display card, whereby the latter may be conveniently supported in standing position when desired, while at the same time 50 permitting of its being conveniently suspended for display, or compacted for shipment or storage as closely as without such attachment; and further, to secure these results with the greatest economy and simplicity of construction and operation. To

this end, the easel leg 10 employed consists merely of a strip of resiliently stiff sheet material such as steel or brass, capable of springing back to determined normal shape after being deflected therefrom. The length 60 of this metal strip, as indicated, is substantially equal to the height of the card; and its upper end 11 is rigidly secured to the upper border of the latter, by means of the doubled-over marginal portions of the sheets 65 as shown; while its lower end 12 is adapted to enter an engaging pocket 13 therefor, formed midway of the width of the card, as indicated, between the doubled-over bottom margins of the sheets and the adjacent 70 border portion of the card; this pocket formation being readily provided by omitting the clenching at such midway portion. The easel leg strip 10 is so formed as to cause its lower portion to naturally project 75 rearward of the card, as indicated in Figs. 1 and 2, when said end 12 is disengaged from the pocket 13; but it may be readily sprung sufficiently to permit of engaging or disengaging it from said pocket, and when 80 thus engaged it is held close to the rear wall of the card. As shown the main portion of the latter intermediate of the border portions 8 thereof, is bulged forward so as to dish the card at the rear and thereby give 85 sufficient room for the engaged easel leg 10 to effectively prevent it from projecting rearwardly and interfering with the card being laid flat upon its back as when no easel leg is provided; while when released 90 from its engagement the leg is adapted to automatically spring to a proper supporting position, and to retain it without bracing. To provide for neatly hanging the card when desired, apertures 15, 15 are provided 95 near the attached upper end of the easel leg, through which a suspending cord, wire, or chain may be passed, the lower end of the leg being kept engaged in the pocket 13 when it is so used. The attachment thus 100 provides a simple and satisfactory supporting device without at all increasing the size of the structure and at a trifling cost.

What I claim is:—

1. A display card comprising contacting 105 sheets of display material and of flangeable backing material, the marginal portions of which are doubled-over rearwardly and clenched against the adjacent border portions thereof; and a flexible easel leg of 110

sheet material having its upper end rigidly clenched by the upper doubled-over border portions of the card sheets, and its lower end removably engaged by an unclenched central portion of the lower doubled-over border portions of said sheets; and adapted to spring rearwardly when released from such engagement.

2. In combination with a display card 10 provided with easel-leg engaging means at the lower border portion thereof, a flexible easel leg of sheet material having its upper

end rigidly fixed to the upper border portion of the card, and its lower end disengageably secured by said engaging means 15 and adapted to spring rearwardly when disengaged therefrom.

In testimony whereof I affix my signature in presence of two witnesses.

HOWARD J. POTTS.
